(57) **CLAIM**

The ornamental design for a guard supporting member for a gabion basket, as shown and described.

DESCRIPTION

FIG. 1 is an isometric view of my new design, a guard supporting member with two (2) prior art gabion baskets shown in broken lines to illustrate the environment of the claimed design and forms no part thereof.

FIG. 2 is an isometric front left top view of the guard supporting member shown in FIG. 1.

FIG. 3 is an isometric front right top view of the guard supporting member shown in FIG. 1.

FIG. 4 is a front view of my new design.

FIG. 5 is a top view of my new design; and,

FIG. 6 is a bottom view of my new design.
